TELEVISION ANTENNA

Marvin P. Middlemark, Rego Park, N. Y.

Application November 15, 1956, Serial No. 43,777

Term of patent 7 years

(Cl. D26—14)

Fig. 1 is a front elevational view of a television antenna showing my new design; and

Figure 2 is a side elevational view thereof.

The dominant portions of my new design reside in those portions shown in full lines.

I claim:

The ornamental design for a television antenna, substantially as shown and described.
